Application June 7, 1934, Serial No. 729,396

16 Claims. (Cl. 66—127)

My invention relates to knitting machines, and particularly to attachments for controlling the movements of yarn-carriers in straight or full-fashioned knitting machines.

5 Fabrics, especially full-fashioned silk stockings, frequently are knit by laying successive courses in repeated sequence from a plurality of cones of like thread to avoid effects, such as the so-called "shadows" or "rings", resulting from knitting the 10 stockings from a single silk body thread, the gauge or evenness of which may depart from normal for a sufficient length to lay several courses side-by-side. By knitting from three threads, a better average texture is obtained.

15 The prior attachments for controlling a knitting machine to knit such fabric in sequential courses from several cones, or to knit other fabrics by any desired number and sequence of operation of carriers and number of cones, have all 20 presented considerable difficulty of construction and operation, and so far as I am aware have all been controlled from a moving element or drive shaft located relatively a substantial distance from the attachment. This feature entails considerable expense and weight, adds a substantial 25 number of parts, allows greater chance for back lash, is more costly to manufacture and assemble, occupies greater space on the machine and in storing and shipping, may not be so readily replaced or repaired, and has other disadvantages.

30 It is therefore, among the objects of my invention to provide a compact, self-contained unit or units, for controlling a knitting machine for the above-mentioned and other purposes, that shall require no mechanical connection to a distant source of movement or drive, as by links, levers and a cam follower to the drive shaft of the knitting machine, or to any other moving part or parts of the machine, but in which the controlling 35 effect imposed by the unit on the machine shall be initiated without such mechanical connection and is preferably derived from, and reacts upon, the immediately adjacent machine parts to be controlled. In other words, the unit which controls the machine parts derives its action from the parts to be controlled and redirects and returns this action to the parts in a mutual exchange or interchange of interacting control effects. Strictly considered, the invention may not reside, at least, not in all of its forms, exclusively in the aforementioned unit, but may also be considered as depending upon slight modification of, or additions to, the parts to be controlled, to provide 40 more effective coaction of the parts with the unit,

as will be understood from the following general outline of the invention:

In a preferred embodiment in a flat knitting machine, such as for knitting full-fashioned stockings, three of the seven or eight yarn-carrier rods usually provided in such a machine, are each provided on the top edge with elements in the nature of cam stops above the top edge. 5

The unit proper of the invention, of which there may be one or two, depending upon the 10 location of the cam stops on the rods, comprises, in a preferred form employing two units, a simple bracket mounted on the usual traveling nut or carriage of the narrowing mechanism, on which bracket are mounted three detent levers, 15 one for each of the above-mentioned cam stops, pivoted about a common axis transverse to the carrier rods. The detent ends of the levers are disposed in slightly-spaced series relation along the carrier rods, each detent lever having a transverse shoulder or detent for longitudinally holding its corresponding cam stop and carrier rod against return movement after it has moved toward that end of the machine. Each detent also extends laterally across the tops of at least the 20 two other carrier rods, and preferably across all of them whereby the rods may be selected for cooperation in any number and combination, and is so shaped that, as one rod reciprocates into or under the unit, it simultaneously releases another 25 rod and is itself latched against return movement. This action is reciprocal and interchangeable between the three selected carrier rods such that they move relative to like units at each end of the machine and are held and released in succession to lay the yarn courses in the proper 30 order. 35

The units may be disposed or arranged in any desirable or suitable place along the yarn carrier rods to coact therewith, as, for example, intermediate the ends of the rods, and may be combined as a single unit per machine. However, as shown, they are operated as two units, one near each end of the machine, and in combination with a yarn carrier selector mechanism near the center of the machine, which successively releases the friction box from the rods as they are held by the units, and reestablishes the friction connection of the box to each rod as it is released. 40 45 50

Another object of the invention is to so operate the unit or units in combination with a yarn carrier selector of such character, or its equivalent, as to provide maximum efficiency, not only of the unit but of the machine, when operating with 55

the unit, and to ensure the corresponding benefit to the fabric.

The unit and the yarn carrier selector are further provided with means for rendering them, at 5 will, inoperative for the multiple-thread knitting operation of the kind herein intended, and to adjust the machine for usual knitting operation.

Another object of the invention is to provide the attachment in such form and construction, 10 as to require substantially minimum change in an existent machine for mounting the attachment thereon.

A further object of the invention is to provide a device of the above-indicated character that 15 shall be simple and durable in construction, economical to manufacture, and effective in its operation.

With these and other objects in view, which 20 will become apparent from the following detailed description of the illustrative embodiments of the invention shown in the accompanying drawings, my invention resides in the novel elements of construction, mechanism and combination of parts in cooperative relationship, as hereinafter 25 more particularly pointed out in the claims.

In the drawings:

Figure 1 is a plan view of a full fashioned stocking knitting machine embodying the invention;

Fig. 2 is a vertical sectional view, taken substantially along the line 2—2 of Fig. 1;

Fig. 3 is a view, taken substantially along the line 3—3 of Fig. 1, of a mechanism for selectively connecting the carrier rods to, and disconnecting them from, the friction box;

Fig. 4 is a view, in front elevation, taken in the direction of an arrow A of Fig. 3;

Fig. 5 is a detail view of certain cam members shown in Fig. 4;

Fig. 6 is a view, taken substantially along the line 6—6 of Fig. 1;

Fig. 7 is a top plan view of, and at right angles to, the structure of Fig. 6;

Fig. 8 is a view, taken substantially along the line 8—8 of Fig. 1, illustrating means for preventing drift of the selector shaft;

Fig. 9 is a view taken along the line 9—9 of Fig. 8;

Fig. 10 is a fragmentary perspective view, illustrating, inter alia, certain of the yarn-carrier rods of the knitting machine, as set up with other parts for drawing yarns from several cones and laying them in sequence to a knitting section;

Fig. 11 is a diagram of one order or sequence in which the thread carriers are operated;

Fig. 12 is a view of the carrier-locking mechanism, taken substantially along the line 12—12 of Fig. 1;

Fig. 13 is an elevation, viewed in the direction of the arrow B in Fig. 12, parts having been broken away;

Fig. 14 is a view, similar to Fig. 13, showing parts thereof in other positions;

Fig. 15 is a view taken substantially along the line 15—15 of Fig. 13;

Figs. 16 and 17 are views, taken substantially along the lines 16—16 and 17—17, respectively, of Fig. 15;

Figs. 18 to 23, inclusive, are structural diagrams, indicating portions of the carrier rods and the units of the invention in successive stages of operation;

Figs. 24 to 29, inclusive, are also diagrams, indicating in broken perspective outline the corresponding stages of the corresponding parts indicated in Figs. 18 to 23, respectively;

Fig. 30 is a view similar to Fig. 12, taken in the direction of the arrow D of Fig. 32, of a modified form of the invention;

Fig. 31 is a view of the structure of Fig. 30, taken substantially along the line 31—31 of Fig. 32;

Fig. 32 is a view, taken in the direction of the arrow C of Fig. 30; and

Fig. 33 is a detail view, taken substantially along the line 33—33 of Fig. 31.

Referring to the drawings, only the parts necessary to a full and complete understanding of the invention are therein shown, the various other parts and mechanisms, and the manner of operation thereof, being well known in the art, and shown and described in detail in the "Reading" Full Fashioned Knitting Machine catalogue, copyright 1929, and published by the Textile Machine Works, Reading, Pennsylvania.

Referring to Figs. 1 to 3, the knitting machine 20 shown embodies eight thread carrier rods 1 to 8, inclusive, although other flat machines employ such rods in various number, and, so far as the present invention is concerned, it is adapted to any machine employing two or a greater number 25 of rods.

In a full-fashioned knitting machine, as selected for illustration, the carrier rods 1 to 8, inclusive, are mounted in parallel spaced relation to each other, for independent longitudinal reciprocation, in a plurality of relatively spaced carrier-rod brackets 10 that are secured to a center bed beam 11, see Fig. 2, which is secured to the main center and end frames 12.

The invention, by way of illustration only, but in a preferred form, involves only three of the thread carrier rods, which, in this instance, have been selected as rods 2, 3 and 5, but which may be members of any other kind or combination thereof.

The rods 2, 3 and 5, Figs. 1, 4 and 10, are provided with thread guides 2a, 3a and 5a, respectively, that receive, and control, individual knitting threads X¹, Y¹ and Z¹, which are drawn by the guides from separate yarn cones X, Y and Z, 45 through usual tensioning and moistening devices, indicated in Fig. 10. These guides lay the respective threads to needles of one and the same group 15 of each knitting section in predetermined order, as indicated in Fig. 11, each for 50 knitting, in the instant case, only a single course of loops at any one time.

The selection of the carrier rods is effected automatically, and, as a matter of illustration, the threads, in the present case, are fed to the needles in the order X¹, Y¹, Z¹, which is repeated in corresponding cycles throughout the knitting of selected courses of the fabric, each thread making only a single course, in its turn, in each cycle.

Above the yarn carrier bars, at substantially 60 the longitudinal center thereof, a carrier rod selector mechanism is provided. This mechanism constitutes, in one aspect of the invention, an element thereof, in combination with other elements, but not being per se a part of the invention, the mechanism being claimed in a copending application of Gustav Gastrich, Serial No. 677,443, filed June 24, 1933, for Yarn feeding mechanism for straight knitting machines, which application is assigned to the Textile Machine Works, Wyomissing, Pa., assignee of the present application. As parts of this mechanism, the carrier rods 2, 3 and 5 are provided with actuating dogs 2b, 3b and 5b, respectively, by which they are selectively and automatically operatively 75

connected to a friction box 14 reciprocated by a friction rod 13. The box 14, although of special construction for cooperation with the dogs 2b, 3b and 5b, as herein appears, is also adapted for 5 operation as a usual friction box in a series of usual boxes (not shown) for manual connection to, and release from, one of the carrier rods. Each of the dogs 2b, 3b and 5b comprises a pair of lugs 16, Fig. 4, spaced longitudinally of the rod 10 to form a recess therebetween for the reception of one or the other of a pair of selector members or fingers 18 and 19, Fig. 3, which are formed on, and project from, the lower end of a plunger head 20 that is slidably mounted in the lower end 15 of a rod-selecting rocker element 22. The head 20 is provided with a stem 21, which is slidably mounted in the selector or rocker 22. The head 20, and the fingers 18 and 19, are adapted for sliding movement in the selector 22, relative to the carrier rods 2, 3 and 5, for effecting engagement and disengagement of the fingers, being maintained in the desired position by means of a spring-pressed detent 23, which is carried by the selector 22 and adapted to enter notches 24 20 and 25, in the stem 21, in spaced relation to each other longitudinally of the stem.

The selector rocker 22 is mounted for pivotal movement on, and relative to, the friction box 14, on a short shaft 26 which is secured in the selector by a set screw 27, with the ends of the shaft 30 extending in opposite directions from the opposite sides of the selector, and pivotally mounted in bearings 28 on arms 29 which are integral with, and extend laterally from, one side of the friction box 14.

The arms 29 are also provided with a second pair of bearings 30, which embrace, and are adapted to be moved along, a selector shaft 31. The shaft 31 extends parallel to the friction rod 13, and to the carrier rods 1 to 8.

The shaft 31 is rotatably journaled in bearings 32, Figs. 8 and 9, on adjustable brackets 33, each of which is pivotally mounted on a bushing 34 that is carried in, and extends laterally from, a bearing 35 on the end of a bracket 36 fixed to the machine frame. The bushings 34, in addition to providing pivoted mounting means for the adjusting brackets 33, provide slidable bearing means for the friction box rod 13.

Each adjustable bracket 33, Fig. 8, is provided with a pair of arms 37 and 38, in the outer ends of which are threaded adjusting screws 39 and 40, respectively. The screw 39 bears against the upper surface of the rigid bracket 36, and the screw 40 bears against the underside of a friction box guide rod 13a, which is secured in, and extends between, the rigid brackets 36, parallel to the friction box rod 13, whereby the brackets 33 may be adjusted about the axis of the rod 13 55 for aligning the selector shaft 31 axially with the bearings 30 carried by the friction box 14.

Adjacent to the bearings 30, Fig. 4, selector cams 41 and 42, see also Fig. 5, are severally provided with sleeve-like hubs 43, which are splined to the shaft 31 and rotatably mounted in the adjacent bearings 33. Each sleeve 43 extends beyond the opposite side of the bearing, at which its particular cam is located, and is provided with a collar 44 secured thereto adjacent to its outer end, to prevent axial movement between the bearing and the cam, whereby, under longitudinal reciprocation of the friction box 14, the cams will accordingly be reciprocated, relative to the selector shaft 31, during each reciprocation 65 of the friction box 14, as it effects longitudinal

movement of one of the carrier rods 2, 3 or 5, through the selector 22 and fingers 18 and 19, to lay the thread controlled by the guide thereon to the needles 15 for the formation of a single course of loops.

At the end of each needle-traversing stroke of reciprocatory movement of the friction box 14, the selector shaft 31 is rotated through an angle of 60°, whereby the carrier rod previously moved by the friction box is released therefrom, and 10 whereby an operative connection is established between the friction box and another thread bar, depending upon the position to which the selector 22, on the friction box 14, is moved by the above-mentioned partial rotation of the shaft 31. 15

The intermittent 60° turns, of the selector shaft 31, cause the cams 41 and 42 to rock the selector 22 about its pivot, to release the connecting finger 18 or 19, as the case may be, from the next preceding operative carrier rod, and to 20 engage one of said fingers to the dog of the subsequent carrier rod next in turn for actuation.

The selective rocking of the selector 22, by the cams 41 and 42, is effected through rollers 41a and 42a, which are, respectively, engaged by 25 the cams 41 and 42, the rollers 41a and 42a being rotatably mounted in angularly spaced relation to each other, and to the axis of the pivot shaft 26 of the selector 22.

The intermittent 60° turns of the selector shaft 30 31 are effected by mechanism shown in Figs. 6, 7, and 2. As shown in Figs. 6 and 7, the selector shaft 31 has, secured thereto, a ratchet wheel 50. A pawl carrier 51 is pivotally mounted on the shaft 31, adjacent to the ratchet wheel 50. A 35 pawl 53 is pivotally mounted, on a pin 52 in the pawl carrier 51. The pawl 53 is normally held in engagement with the ratchet wheel 50, by a spring 54 having one end secured to the pawl and its opposite end secured to the pawl carrier 51. 40

A link 56 is pivotally mounted, at one end, on a pin 55, in the pawl carrier 51, and, at the opposite end, Fig. 2, is pivotally connected, by a pin 57, to one arm 58 of a lever 59. The lever 59 is pivotally mounted on a pin 60, in a bracket 61. 45 that is secured to one of the main longitudinal beams 62 of the machine. The second arm 63, of the lever 59, is provided with a cam follower roller 64, for engagement with the periphery of a cam 65 that is secured to the main cam shaft 50 66 of the machine.

The shaft 66 is adapted to be shogged axially, to effect operation of the point actuating mechanism in usual and well known manner, during which time the thread carrier rods remain idle. 55

To prevent disruption of the predetermined order in which the thread carriers are to be operated, shogging of the shaft 66 moves the cam 65 from under the roller 64, and moves a substantially circular disc 67 into alignment with the roller, whereby rotation of the shaft 66, while effecting the above-mentioned narrowing of the fabric, does not effect rotation of the selector shaft 31.

The pawl 53 is provided with a handle 68, by which, at such times as it may be desirable to knit a plurality of successively interlooped courses of a single thread fed to the needles by a single carrier rod, the pawl may be moved out of operative relation to the ratchet wheel 50, in which case, the pawl 53 is turned about its pivot 52 until the handle 68 of the pawl rests against a lug 69 on the pawl carrier 51. During this movement of the pawl, the spring 54 moves across the center of the pivot pin 52 of the pawl, and

holds the handle 68 against the lug 69, to prevent engagement of the pawl with the ratchet wheel 50.

Longitudinal movement of the carrier rods 1 to 8, inclusive, is limited by stops 70, Fig. 1, carried by narrowing carriages or nuts 71, at the ends of the machine, which are moved longitudinally inwardly of the rods, when transferring stitches, by narrowing screws 72. The screws 72 are actuated, in a usual manner, from the cam shaft 66, after the shaft is shogged axially.

The reciprocations of the friction rod 13 are uniform and greater than the maximum movement required by the friction box 14 to effect 15 complete full needle-traversing movements of the carrier rods, as determined by the positions of the stops 70.

To prevent rebounding of the carrier rods from the stops 70 and to give the yarn carriers a pre-determined lead with respect to the sinkers, each 20 narrowing nut 71 is provided with a guide bracket 73 for a pair of rod arresting levers 74, which cooperate with shoulders 75 of plates 76 on the carrier rods, Fig. 13. As a carrier rod is moved 25 against its stop 70, one of the levers 74 drops behind the corresponding shoulder 75 to prevent rebound of the rod, and is raised to permit movement of a rod in the opposite direction; this mechanism being usual in a machine of this type. 30 Whether the machine is operating to lay consecutive threads from different cones, or is operating from a single cone, as in a usual operation, the arresting levers 74 operate in well known and customary manner.

35 In accordance with the invention, each of the carrier rods 2, 3 and 5, merely as representative of any selected plurality of rods, is individually held against longitudinal movement, except at such time as one of the rods is selected to lay a thread to the needles, and, for this purpose, the rod 2 is provided, as viewed from the front of the machine, at its left end, with a cam stop 102, and, at its right end, with a cam stop 102a; the rod 3 is provided, at its left end, with a cam stop 103, and, at its right end, with a cam stop 103a; and the rod 5 is provided with a left-end cam stop 105 and a right-end cam stop 105a. Each of these cam stops, constituting a combined detent and release element, is provided with an inclined cam surface 77 sloping longitudinally of the rod 45 for releasing, and a notch providing a holding shoulder 89 transversely of the rod and the cam stop for cooperation with, a detent lever of the unit of the invention.

50 This unit, one of which is preferably disposed at each end of the machine, comprises a bracket 80, Fig. 12, having a sleeve 81, by which it surrounds, and slides along, a short rod or shaft 82 that is already present in a standard machine of this type parallel and adjacent to the nut 71. An arm 83 projecting laterally from the sleeve 81 rigidly supports, at its outer end, an open frame 85 disposed in a plane substantially parallel to, and spaced above, the plane of the carrier rod 55 group, as indicated in Fig. 12. The longitudinal sides of this frame extend transversely of the rods, one of the sides transversely to the rods being constituted by a pivot support or shaft 86, and the other by wall 87, cast integrally with the frame and functioning as an anchorage for 60 springs 88. A thick steel strap 78 is bridged between, and fixed to, the frame 85 and the narrowing nut 71, as by screws 79, and, with the bracket arm 83, serves as a rigid base for the unit.

75 Detent levers 90, of bell-crank form, are piv-

oted on the shaft 86, each having an arm or arm branches 91 extending perpendicularly to the rods, between which branches and the anchorage wall 87 of the frame, the springs 88 are connected under tension. Each of the detent levers 90 is, as viewed laterally thereto in the direction of the shaft 86, of a usual substantially L-shape or profile. However, as viewed in plan, as in Fig. 15, the levers are severally of other shapes. The center bell crank has only one of the arms 91, 10 and is biased by only one of the springs 88. Its other arm 93 is also single, extending along the rods, and has a transverse free-end head 94, rendering the arm 93 of substantially T-shape in plan.

The lever, next adjacent to the center lever, has a pair of spring-mounting arms 91 at opposite sides of the center lever, and a pair of the arms 93, also at opposite sides of the center lever, which are connected by a member 2c, thus rendering this lever of substantially U-shape in plan, having its pivot connections to the shaft 86 at the free ends of its double arm 93, and a single or branch arm 91 projecting from each of these free ends.

The third, or outermost lever, is constructed similarly to the intermediate lever, except that it is larger, and has a member 5c forming the closed end of its U-shaped plan. The single T-head center lever arm 93 has a cross-head member 3c fixed thereto, similar to the members 2c and 5c. Thus, the corresponding arms 93 of the levers are in the nature of an assembly or group of arms nested one with another, in substantially a common plane with the inner or T-head arm at the center, an intermediate arm of U-shape embracing the T-head arm, and a larger or outer arm of U-shape embracing the intermediate arm. This construction is provided for symmetry and balance.

40 The transverse ends of the frame 85, parallel to the carrier rods, are provided with bearings 95 for a shaft 96 that is disposed in spaced parallel relation to, and between, the sides of the frame and extends across the carrier rods and bell-crank levers. The shaft 96 is thus disposed in the space defined by the springs 88, the arms 91, the arms 93 and the spring-anchorage frame side 87.

50 In this space, between the frame end walls, the shaft 96 has fixed thereto, a cam member 97, which is adapted to cooperate with the ends of the adjusting screws 98 in the bell-crank arms 91, and has a fixed operating handle 99 outside the frame 80.

55 By turning the handle 99 clockwise, as viewed in Fig. 13, to the position indicated, the cam 97 allows free movement of the levers for cooperation with the cam stops 102, 103 and 105 on the carrier rods, but acts as a limit stop for the levers. By turning the handle 99 counter-clockwise, as viewed in Fig. 14, to the position indicated, the cam 97 holds all of the bell cranks in raised or inoperative position relative to the carrier rods. By turning the screws 98, the levers may be individually adjusted with respect to the corresponding cam stops 102, 103 and 105.

60 As better seen in Figs. 16 and 17, the bell-crank cross-head elements 2c, 3c and 5c, which may 70 be removably secured to the levers by screws 100, are in the nature of combination selectors, or combined detent and detent release arms, whereby each holds one of the carrier rods against longitudinal movement but is movable by one of the 75

other rods to release the rod it holds. This action, since these selectors extend across the carrier rods closely adjacent thereto, is effected by providing each selector with a transverse detent or holding portion 2e, 3e or 5e, for its operating rod and a detent-releasing arm 2g, 3g or 5g opposite the rod selected to release it. In the particular combination illustrated, the detent and arm on the member 5c are spaced 10 apart, as are the detent and arm on the member 2c, but the detent and arm portions 3e and 3g on the member 3c are side-by-side parts of a single portion depending from the under side of the member, as seen in dotted lines in Fig. 17, but as shown as laterally-spaced separate depending portions in Figs. 24 to 26, inclusive, for clarity.

The corresponding selectors 2d, 3d and 5d, at the right-hand end of the machine, as viewed 20 from the front, are provided, respectively, with detents 2f, 3f and 5f, and with detent-release arms 2h, 3h and 5h. By this arrangement, the carrier rods may reciprocate longitudinally back and forth between the units at the respective 25 ends of the machine, in a given sequence, and provide their own releasing and holding force. Thus the units are substantially self-contained, or self-operative, so far as outside connection to any movable element is concerned, and the detents and detent-release cams may be rearranged 30 to operate any desired selection of the carrier rods in any desired sequence. Although, preferably operated in combination with a selector mechanism, as shown at the center of the machine for selectively connecting and releasing the carrier rods from the friction box 14, the self-operated unit selector mechanism, as shown at the ends of the rods, will operate in a machine 35 where the above-mentioned center selector is either omitted, and the rods operated by usual friction boxes, or is replaced by another mechanism for effecting the same or other results.

Although the cam stops 102 to 105a, inclusive, are of the same general construction, being suitably secured to the carrier rods, as by pins or rivets 101, by reason of the offset relation of the selector elements 2c, 3c and 5c, at the left-end of the machine, and the like relation of the elements 2d, 3d, and 5d, at the right-end of the machine, 45 and also, by reason of the sequence selected in this instance, they are of slightly different shapes and dimensions, in accordance with the relations thereof to the various detents and detent-release arms; the cam stops 103 and 103a on the rod 3 having extensions 84, on which one of the elements 5c and 5d rests, when the rod 3 is in held 50 position at the corresponding end of the machine. Each of the cam stops 102 to 105a, inclusive, has a holding notch intermediate its ends providing 55 an upright holding shoulder or face 89, against which one of the detents 2e, 3e etc., bears in the holding position of the detent; these surfaces, although positively holding or locking the rods under normal operating conditions, in the manner 60 above stated, nevertheless are preferably arranged, as by the slope thereof relative to the direction of movement of the carrier rods, by the position thereof relative to the pivot shaft 86, by the coefficient of friction thereof, or by 65 the weight of the parts or the strength of the springs 88 or other factors, so as, under abnormal conditions, to release the corresponding rods under the force of the driving means, when the corresponding detent-release arm has not been raised, as where the selector mechanism at the

center of the machine becomes damaged or disarranged or becomes asynchronous to select and drive a rod out of sequence.

Referring to the sequence diagrams of Figs. 18 to 23, inclusive, and of Figs. 24 to 29, inclusive, Figs. 18 and 24 indicate a step or stage temporarily existent in the sequence of operation, in which the carrier rod 2 is being held by the selector element 2c, at the left-hand unit, as viewed in Figs. 18 and 24, while the carrier rod 3 is moving toward the right, and carrier rod 5 is being held by selector element 5d at the right-hand unit.

At this stage, the rod 3 is moving to the right, as viewed in Figs. 18 and 24, between and not held by either of the end units, the rod 2 is being held at the left-hand unit by the detent 2e and the arm 2g is in position to be raised by the surface 77 of the cam stop 105 to the top of the latter. The rod 5 is being held at the right-hand unit by the detent 5f and the arm 5h is in a position to be raised by the surface 77 of the cam stop 103a.

At the left, as viewed in Figs. 18 and 24, the detent 3e is being held in an upper unlatched position above the position previously occupied by the cam stop 103 before release by an action of the surface 77 of the cam stop 102 against the arm 3g. At the right, the detent 2f is being held in upper or unlatched position over the position previously occupied by the cam stop 102a before release by the action of the surface 77 of the cam stop 105a against the arm 2h.

At the left, as viewed in Figs. 18 and 24, the selector element 5c is in lowered position, with its arm 5g in the space vacated by the cam stop 103, and its detent 5e ready to be raised by the surface 77 of the cam stop 105 and dropped behind the shoulder 89 of the cam stop 105, when the rod 5 moves to the left from its held position at the right-hand unit. At the right-hand unit, the selector 3d is in lowered position, with its arm 3h in the space previously vacated by the cam stop 102a, and its detent 3f ready to be raised by the surface 77 of the cam stop 103a and dropped behind the shoulder 89 of the cam stop 103a when the latter arrives after completing the movement indicated.

In Figs. 19 and 25, carrier rod 3 has moved into the right-hand unit, and is being held against return movement by the selector element 3d, simultaneously with release of the carrier rod 5 by the rod 3, the rod 5 being indicated as at a position occupied during its consequent left-hand reciprocation movement.

At this stage, the rod 5 having been released from its detent 5f by the action of the surface 77 of the cam stop 103a against the arm 5h, is moving to the left, as viewed in Figs. 19 and 25, between the end units, the rod 3 is being held at the right-hand unit by the detent 3f and the arm 3h is in position to be raised by the surface 77 of the cam stop 102. The rod 2 is still being held at the left-hand unit by the detent 2e and the arm 2g is in position to be raised by surface 77 of the cam stop 105.

At the right, as viewed in Figs. 19 and 25, the detent 5f is being held in an upper unlatched position above the position previously occupied by the cam stop 105a before release by the action of the surface 77 of the cam stop 103a against the arm 5h. At the left, the detent 3e is being held in upper or unlatched position over the position previously occupied by the cam stop 103 before release by the action of the surface 77 of the cam stop 102 against the arm 3g.

At the right, as viewed in Figs. 19 and 25, the selector element 2d is in lowered position, with its arm 2h in the space vacated by the cam stop 105a, and its detent 2f ready to be raised by the surface 77 of the cam stop 102a and dropped behind the shoulder 89 of the cam stop 102a, when the rod 2 moves from its held position at the left-hand unit. At the left-hand unit, the selector element 5c is in lowered position with its arm 5g in the space previously vacated by the cam stop 103, and its detent 5e ready to be raised by the surface 77 of the cam stop 105 and dropped behind the shoulder 89 of the cam stop 105 when the latter arrives after completing the movement indicated.

In Figs. 20 and 26, the carrier rod 5 has reached the left-hand unit, as viewed in these figures, to be latched by the selector element 5c, and to release the carrier rod 2 from the element 2c for the right-hand movement indicated.

At this stage, the rod 2, having been released from its detent 2e, by the action of the surface 77 of the cam stop 105 against the arm 2g, is moving to the right, as viewed in Figs. 20 and 26, the rod 5 is being held at the left-hand unit by the detent 5e and the arm 5g is in position to be raised by the surface 77 of the cam stop 103. The rod 3 is being held at the right-hand unit by the detent 3f and the arm 3h is in position to be raised by surface 77 of the cam stop 102a.

At the left, as viewed in Figs. 20 and 26, the detent 2e is being held in an upper unlatched position over the position previously occupied by the cam stop 102 before release by the action of the surface 77 of the cam stop 105 against the arm 2g. At the right, the detent 5f is being held in upper or unlatched position over the position previously occupied by the cam stop 105a before release by the action of the surface 77 of the cam stop 103a against the arm 5h.

At the left, as viewed in Figs. 20 and 26, the selector 3c is in lowered position, with its arm 3g in the space vacated by the cam stop 102, and its detent 3e ready to be raised by the surface 77 of the cam stop 103 and dropped behind the shoulder 89 of the cam stop 103, when the rod 3 returns from its locked position at the right-hand unit. At the right-hand unit, the selector 2d is in lowered position, with its arm 2h in the space previously vacated by the cam stop 105a, and its detent 2f ready to be raised by the surface 77 of the cam stop 102a and dropped behind the shoulder 89 of the cam stop 102a when the latter arrives after completing the movement indicated.

In Figs. 21 and 27, the carrier rod 2 has reached the right-hand unit to be latched by the selector element 2d, and to release the rod 3 from its selector 3d, for the left-hand reciprocation movement indicated.

At this stage, the rod 3 having been released from its right-hand detent 3f, as seen in Figs. 21 and 27, by the action of the surface 77 of the cam stop 102a against the arm 3h, is moving to the left, the rod 2 is being held at the right-hand unit by the detent 2f, and the arm 2h is in position to be raised by the surface 77 of the cam stop 105a. The rod 5 is being held at the left-hand unit by the detent 5e and the arm 5g is in a position to be raised by the surface 77 of the cam stop 103.

At the right, as viewed in Figs. 21 and 27, the detent 3f is being held in upper unlatched position above the position previously occupied by the cam stop 103a before release by the action

of the surface 77 of the cam stop 102a against the arm 3h. At the left, the detent 2e is being held in upper or unlatched position above the position previously occupied by the cam stop 102 before release by the action of the surface 77 of the cam stop 105 against the arm 2g.

At the right, as viewed in Figs. 21 and 27, the selector 5d is in lowered position, with its arm 5h in the space vacated by the cam stop 103a, and its detent 5f ready to be raised by the surface 77 of the cam stop 105a and dropped behind the shoulder 89 of the cam stop 105a, when the rod 5 returns from its locked position at the left-hand unit. At the left-hand unit, the selector 3c is in lowered position, with its arm 3g in the space previously vacated by the cam stop 102, and its detent 3e ready to be raised by the surface 77 of the cam stop 103 and dropped behind the shoulder 89 of the cam stop 103 when the latter arrives after completing the movement indicated.

In Figs. 22 and 28, the carrier rod 3 has reached the left-hand unit, as viewed in these figures, for latching by the selector element 3c, and to release the rod 5, from its selector 5c, for the right-hand reciprocation movement indicated.

At this stage, the rod 5 having been released from its left-hand detent 5e by the action of the surface 77 of the cam stop 103 against the arm 5g, is moving to the right, the rod 3 is being held at the left-hand unit by the detent 3e and the arm 3g is in position to be raised by the surface 77 of the cam stop 102. The rod 2 is being held at the right-hand unit by the detent 2f and the arm 2h is in a position to be raised by the surface 77 of the cam stop 105a.

At the left, as viewed in Figs. 22 and 28, the detent 5e is being held in an upper unlatched position above the position previously occupied by the cam stop 105 before release by the action of the surface 77 of the cam stop 103 against the arm 5g. At the right, the detent 3f is being held in upper or unlatched position above the position previously occupied by the cam stop 103a before release by the action of the surface 77 of the cam stop 102a against the arm 3h.

At the left, as viewed in Figs. 22 and 28, the selector 2c is in lowered position, with its arm 2g in the space vacated by the cam stop 105, and its detent 2e ready to be raised by the surface 77 of the cam stop 102 and dropped behind the shoulder 89 of the cam stop 102, when the rod 2 returns from its locked position at the right-hand unit. At the right-hand unit, the selector 5d is in lowered position, with its arm 5h in the space previously vacated by the cam stop 103a, and its detent 5f ready to be raised by the surface 77 of the cam stop 105a and dropped behind the shoulder 89 of the cam stop 105a when the latter arrives after completing the movement indicated.

In Figs. 23 and 29, the carrier rod 5 has again reached the right-hand unit, as in Figs. 18 and 24, after a complete cycle of left and right travel, to be held by the selector element 5d, and to release the carrier rod 2, for left-hand movement, for positioning, as in Figs. 18, 24 and 19, 25, when it will be again released, as in Figs. 20 and 26.

At this stage, as viewed in Figs. 23 and 29, the rod 2, having been released from its right-hand detent 2f by the action of the surface 77 of the cam stop 105a against the arm 2h, is moving to the left, the rod 5 is being held at the right-hand unit by the detent 5f and the arm 5h is in position to be raised by the surface 77 of the cam stop 103a. The rod 3 is being held at the left-hand unit by the detent 3e and the arm 3g is in a

position to be raised by the surface 77 of the cam stop 102.

At the right, as viewed in Figs. 23 and 29, the 5 detent 2f is being held in an upper unlatched position, over the position previously occupied by the cam stop 102a before release by the action of surface 77 of the cam stop 105a against the arm 2h. At the left, the detent 5e is being held in upper or unlatched position over the position 10 previously occupied by the cam stop 105 before release by the action of the cam stop 103 against the arm 5g.

At the right, as viewed in Figs. 23 and 29, the 15 selector 3d is in lowered position, with its arm 3h in the space vacated by the cam stop 102a, ready to be raised by the surface 77 of the cam stop 103a and dropped behind the shoulder 89 of the cam stop 103a, when the rod 3 returns from its locked position at the left-hand unit. At the left-hand 20 unit, the selector 2c is in lower position, with its arm 2g in the space vacated by the cam stop 105, and its detent 2e ready to be raised by the surface 77 of the cam stop 102 and dropped behind the shoulder 89 of the cam stop 102 when the latter 25 arrives after the rod 2 completes the movement indicated.

As indicated more clearly in Figs. 28 and 29, the cam stop 103 is provided with a side plate 106 bridging the notch which provides the detent 30 shoulder 89. This plate 106 permits the detent 3e of the selector 3c to drop into the notch to engage the shoulder 89 of the cam stop 103 but causes the arm 5g to slide over such notch.

The cam stop 103a is also provided with a like 35 side plate 106a for permitting the detent 3f to drop into the notch providing the shoulder 89 in the cam stop 103a, and to cause the arm 5h to slide over the notch, as indicated more clearly in Figs. 25 and 26.

40 Figs. 30 and 33, inclusive, illustrate a simplified form of the invention in which the detent-release arms of the above-described structure are omitted, and detents 2i, 3i and 5i, corresponding to the detents 2e, 3e and 5e, are provided with sloping 45 holding surfaces 107 cooperating with sloping surfaces 108 of the cam stops 109 on the carrier rods 110, whereby, the individual rods, when they are selectively connected to the friction box 14, may be pulled out of the held positions.

50 In the structure of Figs. 30 to 33, a narrowing nut or carriage 112, on a narrowing screw 114, has an arm 115, between which and a plate 116, secured to the nut, as by screws 117, a pivot pin 118 extends, which is held in position by a screw 119. Usual end stops 120, for the several rods, 55 are pivoted on the pin 118 and have handles 121 for movement about the pin from the operative position illustrated to an inoperative position against a pin 122 extending between the arm 115 and the plate 116.

A plate-like bracket 124, held to the arm 115 by the screw 119 and by pins 125 about the pin 118, and extending along the carrier rods 110, 60 supports three pins 127, 128 and 129 adjacent to one end thereof. On the pin 127, are supported bell-crank levers 130 having arms 132 carrying the detents 2i, 3i and 5i, and arms 133 between which and the pin 129 are connected springs 135 for 65 biasing the levers clockwise, or toward the cam stops 109, as viewed in Fig. 32. Screws 136 secure the detents 2i, 3i and 5i, to the arms 132 and are disposed in slots 137 in the arms whereby the 70 detents may be accurately set relative to the cam stops 109.

The pin 128 carries a handle 139 and a cam 140 against which bear screws 142 in the arms 133. By adjusting the screws 142, the elevation of the 75 detents may be varied relative to the cam stops 109. A strap-like member 143 joins and braces 10 ends of the pins 127, 128 and 129, and operates as a stop, against one edge of which, see Fig. 33, a lateral projection or lug 144 on the handle 139 has two positions, as indicated in full and broken lines, respectively, for determining the limiting 15 positions of the cam 140 about the axis of the pin 128. In the position indicated in Fig. 32, the 20 detents are in operative position to receive, hold and release the carrier rods through the intermediary of the cam stops 109, and, when the handle 139 is turned to the left from the position indicated in Fig. 32 or to the right, as seen in Fig. 33, the cam 140 moves against the screws 142 to thereby move the bell-crank levers and the 25 detents to inoperative position, as in the form first 30 above described. Near the ends of its movement the cam 140 has portions upon which the ends of the screws 142 rest and tend to hold the cam in position. This form of the invention has the 35 features of fewer parts and lighter weight, with attendant advantages such as economy, simplicity and ready repair.

Of course, the improvements specifically shown and described, by which I obtain the above results, can be changed and modified in various ways 40 without departing from the scope of the invention herein disclosed and hereinafter claimed.

I claim:

1. In a straight knitting machine comprising 45 yarn carrier rods, means for reciprocating the carrier rods, mechanism for selectively connecting certain of the carrier rods to, and releasing them from, the reciprocating means, and slip-connection means operated by said certain carrier rods for holding the same against, and slip 50 releasing them for, yarn-carrying movement in accordance with the selected releases and connections, respectively, effected by said mechanism, each carrier rod, as selected by said mechanism for release by said holding means for reciprocation by said reciprocating means, depending entirely for such release upon its own direct action on the holding means to force the latter to release the rod.

2. In combination, in a knitting machine comprising carrier rods, a bracket including a base support, bearings, a pivot support and a spring anchorage, a plurality of levers of L-profile, certain of which each have one arm of the L of U-plan nested one within another about a single-branch corresponding L-arm of a center lever, with the free ends of the U-arms and the corresponding end of said center lever pivotally mounted on said pivot support, the other arms of the L of each U-arm lever each being double and projecting from the free ends of the U at opposite sides of a single corresponding arm of the center lever, tension springs extending one from each branch of said double arms and from the corresponding center-lever arm to said anchorage, elements at the closed ends of the U-levers and at the corresponding end of the center lever for co-operation with the carrier rods, and means including an operating member pivotally mounted on said bracket bearings for moving all of the 60 levers against the action of said springs to inoperative position and holding the levers in said position.

3. In a knitting machine, a plurality of yarn-carrier rods, means for reciprocating the rods,

members biased toward the rods having portions for locking certain of the rods and portions for actuation by other of the rods for unlocking said lock portions, and elements on the rods for cooperation with said lock and release portions, one of said elements and one of said portions being adapted to pass each other while engaged under said bias each without affecting the other in its operative function.

4. In combination, in a knitting machine comprising carrier rods, a bracket including a base support, bearings, a pivot support and a spring anchorage, a plurality of levers of L-profile, certain of which each have one arm of the L of U-plan nested one within another about a single-branch corresponding L-arm of a center lever, with the free ends of the U-arms and the corresponding end of said center lever pivotally mounted on said pivot support, the other arms 20 of the L of each U-arm lever projecting from the free ends of the U beside a corresponding arm of the center lever, springs extending from said other and said corresponding arms to said anchorage, elements at the closed ends of the 25 U-levers and at the corresponding end of the center lever for cooperation with the carrier rods, and means including an operating member pivotally mounted on said bracket bearings for moving all of the levers against the action of 30 said springs to inactive position and holding the levers in said position.

5. In a straight knitting machine, a narrowing spindle, a nut on the spindle, yarn carrier rods, and a latch mechanism for the carrier rods including a support rigidly mounted on the nut 35 and therewith completely surrounding paths of longitudinal reciprocation of the rods, a pin on said support disposed over said paths a distance therefrom and extending transversely thereto, 40 a plurality of bell-crank levers pivotally mounted on said pin carrying on one arm along the rods a receiving portion, latch members provided one for each bell crank and means for rigidly detachably connecting each latch member to its 45 corresponding said receiving portion for holding cooperation with a carrier rod, the other arm of each bell crank projecting substantially perpendicularly to the rods, a spring anchorage on the support transverse to the rods, elements provided one for, and adjustably mounted on, each 50 of said perpendicular lever arms, tension springs connected between said perpendicular arms and said anchorage for biasing the latch members toward the carrier rods, and means including a 55 member rotatively mounted on said support between said perpendicular bell-crank arms and said anchorage about an axis transverse to the rods and cooperating with said adjustably-mounted elements for holding the latch members in 60 inactive position and releasing them for cooperation with the rods.

6. In a knitting machine, yarn carriers, a support, a spring anchorage, levers of L-profile certain of which have arms of U-plan nested one 65 within another with the free ends of the U-arms pivotally mounted on said support, the other arms of each U-arm lever projecting from the free ends of the U, springs extending from said other arms to said anchorage, elements at 70 the closed ends of the U-levers for cooperation with the yarn carriers, and means for moving the levers against the action of the springs to, and holding the levers in, inactive position.

7. In a knitting machine, yarn carriers, a support, a spring anchorage, levers of L-profile in-

cluding a lever having an arm of T-plan and a lever having a corresponding arm of U-plan about the T-arm pivoted at the free ends of the U and at the free end of the control leg of the T, respectively, on said support, the other arms 5 of the U-arm lever projecting from the free ends of the U and the other arm of the T-arm lever projecting from the free end of said leg, springs extending from said other arms to said anchorage, elements at the closed ends of the U-lever 10 and at the cross head of the T-lever for cooperation with the yarn carriers, and means for moving the levers against the action of the springs to, and holding the levers in, inactive position.

8. In a straight knitting machine, a narrowing 15 carriage, yarn carrier elements, and a latch mechanism for the carrier elements including a support on the carriage, bell-cranks pivotally mounted on the carriage each having on one arm along the carrier elements a receiving portion, a 20 latch member for each bell-crank and means for detachably connecting it to the corresponding receiving portion for holding cooperation with a carrier element, a spring anchorage on the support, means adjustably mounted on the other 25 arm of each bell-crank, springs connected between said other arms and said anchorage for biasing the latch members toward the carrier elements, and means including a member turn- 30 ably mounted on said support and cooperating with said adjustably-mounted means for holding the latch members in inactive position and releasing them for cooperation with the carrier elements.

9. In combination, in a straight knitting machine, 35 yarn carrier rods, actuating means including friction box means for reciprocating the carrier rods, mechanism for selectively connecting certain of the carrier rods to, and disconnecting them from, the friction box means, and rod 40 movement control means controlled by said selector mechanism for holding the rods against, and releasing them for, yarn carrying movement in accordance with the selected disconnections and connections, respectively, effected by said 45 mechanism, to release each rod selected for reciprocation only after the completion of the stroke of the next previously reciprocated rod.

10. In combination, in a straight knitting machine, 50 yarn carrier rods, actuating means including friction box means for reciprocating the carrier rods, mechanism for selectively connecting certain of the carrier rods to, and disconnecting them from, the friction box means, and holding 55 element responsive to operation of said mechanism independently of any selectively operated means other than the rods between said mechanism and the holding elements for holding the rods against, and releasing them for, yarn carrying movement in accordance with the selected disconnections and connections, respectively, effected by said mechanism.

11. In combination, in a straight knitting machine, 60 yarn carrier rods, actuating means including friction box means for reciprocating the carrier rods, mechanism for selectively connecting certain of the carrier rods to, and disconnecting them from, the friction box means, and rod movement control means responsive to operation of said mechanism and unaffected by any other 70 rod for holding each rod against, and releasing it for, yarn carrying movement in accordance with a selected disconnection and connection, respectively, effected by said mechanism.

12. In combination, in a straight knitting ma- 75

- chine, yarn carrier rods, actuating means including friction box means for reciprocating the carrier rods, mechanism for selectively connecting certain of the carrier rods to, and disconnecting them from, the friction box means, and rod movement control means deriving its operating force through said selector mechanism for holding the rods against, and releasing them for, yarn carrying movement in accordance with the selected disconnections and connections, respectively, effected by said mechanism to release each rod selected for reciprocation only after the completion of the stroke of the next previously reciprocated rod.
13. In combination, in a straight knitting machine, yarn carrier rods, actuating means including friction box means for reciprocating the carrier rods, mechanism for selectively connecting certain of the carrier rods to, and disconnecting them from, the friction box means, and rod movement control means controlled by said selector mechanism for holding the rods against, and releasing them for, yarn carrying movement in accordance with the selected disconnections and connections, respectively, effected by said mechanism, each release of a rod by said control means occurring after the selection by said mechanism of such rod for connection to the actuating means.
14. In combination, in a straight knitting machine, yarn carrier rods, actuating means including friction box means for reciprocating the carrier rods, mechanism for selectively connecting certain of the carrier rods to, and disconnecting them from, the friction box means, and holding elements controlled by said selector mechanism for holding the rods against, and releasing them for, yarn carrying movement in accordance with
- the selected disconnections and connections, respectively, effected by said mechanism, each release movement of any of said holding elements occurring substantially simultaneously with the first movement of the selected carrier rod in its operative stroke.
15. In a knitting machine, a plurality of yarn-carrier rods, means for reciprocating the rods, members biased toward the rods having portions for locking certain of the rods and portions for actuation by other of the rods for unlocking said lock portions, means for preventing engagement of the rods by said portions under said bias, elements on the rods for engaging said portions to effect said locking and unlocking operations including an element on one of the rods having a lock shoulder and intercepting the paths of movement of one of the locking portions and one of said unlocking portions, and means for preventing engagement between said lock shoulder and said one unlocking portion.
16. In a knitting machine, a plurality of yarn-carrier rods, means for reciprocating the rods, members biased toward the rods having portions for locking certain of the rods and portions for actuation by other of the rods for unlocking said lock portions, means for preventing engagement of the rods by said portions under said bias, elements on the rods including notches for receiving said locking portions to effect said locking operation and cam surfaces for operating said unlocking portions to effect said unlocking operations, one of said notches being in the path of movement of one of said unlocking portions, and bridging means enabling said one unlocking portion to cross said one notch.

RUDOLPH ANKE.
